COMBINED TUNING CONTROL AND SPEAKER

Anthony J. Rich, 5650 S. Green St., Chicago 21, Ill.

Filed Nov. 14, 1963, Ser. No. 77,433

Term of patent 14 years

(Cl. D26—13)

FIG. 1 is a top plan view of a combined tuning control and speaker showing my new design;

FIG. 2 is a left-hand side elevational view thereof;

FIG. 3 is a right-hand side elevational view thereof;

FIG. 4 is a bottom plan view thereof;

FIG. 5 is a front elevational view thereof; and

FIG. 6 is a rear elevational view thereof.

I claim:

The ornamental design for a combined tuning control and speaker, substantially as shown.
